(57) **CLAIM**

The ornamental design for a camouflage swimming pool chlorinator top, as shown and described.

DESCRIPTION

FIG. 1 is a top, plan view of one embodiment of a camouflage swimming pool chlorinator top incorporating the new

design simulating, by shading, in miniature: a golf green, cup, sand traps, and rolling fairway approach to a sloping green located on a simulated island;

FIG. 2 is an off-angle, perspective view of one aspect of the camouflage swimming pool chlorinator top of FIG. 1 additionally simulating, by shading, golf course rough and shoreline rocks in relationship to a conventional swimming pool chlorinator base shown in broken line which is for illustrative purposes only and forms no part of the claimed design;

FIG. 3 is an off-angle, perspective view of a second aspect of the camouflage swimming pool chlorinator top of FIG. 1 additionally simulating, by shading, a timber retaining wall; FIG. 4 is an off-angle, perspective view of a third aspect of the camouflage swimming pool chlorinator top of FIG. 1; FIG. 5 is an off-angle, perspective view of a fourth aspect of the camouflage swimming pool chlorinator top of FIG. 1; FIG. 6 is an underside plan view of the camouflage swimming pool chlorinator top of FIG. 1 showing the cap locking mechanism in broken line for illustrative purposes only and forms no part of the claimed design;

FIG. 7 is an exploded off-angle perspective view of the FIG. 1 aspect of the camouflage swimming pool chlorinator top relative to a conventional swimming pool chlorinator which is for illustrative purposes only and forms no part of the claimed design; and,

FIG. 8 is an off-angle, perspective view of one aspect of a second embodiment of a camouflage swimming pool chlorinator top according to the principles of the present invention incorporating in miniature, a flagstick.

The broken line showings of a conventional swimming pool chlorinator in FIGS. 2-7 are for illustrative purposes only and form no part of the claimed design.
